UNITED STATES PATENT OFFICE

2,399,316

FLUID METER

William F. Berck, Oakland, Calif., assignor to
 Ralph N. Brodie Company, Oakland, Calif., a
 corporation of California

Application March 6, 1944, Serial No. 525,264

4 Claims. (Cl. 73—242)

This invention relates to fluid meters of the type shown in United States Letters Patent No. 1,895,318.

Meters of the type disclosed in the aforesaid Letters Patent of the United States are provided with a pair of parallel cylinders, each of which is formed with inlet and outlet ports in its peripheral wall extending longitudinally thereof. A reciprocable and oscillatory piston is mounted in each cylinder, and each piston is formed with ports in its peripheral wall to some extent complementary to the ports formed in the cylinders. The piston ports communicate with opposite ends of the piston and are intended to register with the cylinder ports as the piston reciprocates and oscillates in the cylinder. The arrangement and the timing of the registering of the ports is such that as liquid enters through the inlet ports and through the registered piston ports into one end of the cylinder, the piston will be moved by the pressure of such fluid endwise to displace the liquid at the other end of the cylinder. The displaced liquid will discharge of course, through the piston ports and cylinder outlet ports which are in register. Each piston is connected to a crank mechanism so that as it moves endwise, it likewise moves circumferentially to properly synchronize the registration of the piston and cylinder ports.

The length of the crank stroke and the relative positions of the piston and cylinder ports is such that just prior to the end of the piston displacement stroke, the piston ports are placed out of register with the cylinder ports, and this closing of the ports occurs just prior to crank dead center. As the two pistons are connected together with the crank mechanism and are set at ninety degrees apart, the opposite piston will move the one which is on dead center over dead center so that its ports will oppositely register with the cylinder ports so as to move the piston in the opposite direction and displace the liquid in the opposite end of the cylinder. The cylinder and piston ports must be fully out of register before dead center or before the end of one displacement stroke, and cannot be opened until past dead center on the succeeding displacement stroke for the reason that it is mechanically impossible to maintain an effective seal by the piston between the inlet and outlet cylinder ports exactly at dead center.

Therefore, some compression results in that end of the cylinder from which the fluid has just been displaced, and a tendency to create a vacuum occurs between the opposite end of the piston and the opposite end of the cylinder at the end of

each displacement stroke between the closing of the ports and dead center. Likewise, a tendency to produce a partial vacuum occurs between the end of the piston and cylinder from which liquid has just been displaced and some compression results between the opposite ends of the piston and cylinder between the dead center and the opening or registry of the piston and cylinder ports at the commencement of each displacement stroke. The portion of the strokes between closing of the ports and dead center and between dead center and the opening of the ports is an amount represented by the amount of circumferential piston face which must overlap the edges of the cylinder ports to effect a seal, and thereby prevent flow of fluid directly between the inlet and outlet cylinder ports, which flow, of course, will not be measured by the meter nor shown in its counting mechanism.

It is the principal object of the present invention to provide a meter of the character referred to which is of a construction eliminating compression and tendency to create a vacuum at the ends of the piston strokes, while maintaining a fully effective seal between the inlet and outlet cylinder ports.

One form which the invention may assume is exemplified in the following description and illustrated by way of example in the accompanying drawings, in which:

Fig. 1 is a view partly in end elevation and transverse section through a meter embodying the preferred form of my invention.

Fig. 2 is a transverse sectional view through the meter shown in Fig. 1, taken on the line 2—2 of Fig. 3.

Fig. 3 is a bottom view of one of the cylinders of the meter, with parts broken away and in section to more fully disclose certain features of construction.

Fig. 4 is a perspective view of one of the pistons employed, with parts broken away and in section to more clearly disclose its construction.

Figs. 5, 6, 7, 8, 9, 10, 11 and 12 are diagrammatic views showing the manner in which the main and auxiliary ports of the pistons co-act with the main and auxiliary ports of the cylinders.

Referring more particularly to the accompanying drawings, 10 indicates a fluid meter of the displacement type and generally of the character of the fluid meter shown in the aforesaid Letters Patent of the United States. This meter comprises a meter casing 11 having head members 12 at the ends thereof. The meter casing 11 is

formed with an intake connection 14, which communicates with an intake chamber 15 within the casing. The meter casing is also formed with an outlet connection communicating with an outlet chamber 17 formed within the casing and separated, of course, from the inlet chamber. Auxiliary passages J are likewise formed in the casing 11 and are separate from the intake and outlet chambers 15 and 17.

Formed within the meter casing are two metering cylinders 19 which are arranged in parallelism and which are identical in construction, as will be described. The peripheral wall of each cylinder 19 is formed with four main ports E, F, G and H. These ports include two inlet ports E and F and two outlet ports G and H. The inlet ports E and F both form a means of communication between the inlet chamber 15 and the interior of the cylinder 19, and the outlet ports G and H form a means of communication between the interior of the cylinder 19 and the outlet chamber 17. The inlet ports E and F are formed substantially midway between the ends of the cylinder at diametrically opposite sides thereof, while the outlet ports G and H are formed at diametrically opposite points at the top and bottom of the cylinder 19 and substantially midway between the ends thereof, as is illustrated. Each cylinder is formed with the auxiliary passages or ports J forming a communication between the ends of the cylinder and the outlet ports through the medium of piston ports in the associated piston at a proper time during the cycle of the piston operation.

Reciprocably mounted in each cylinder 19 is a reciprocable and oscillatory piston 20, most clearly illustrated in Fig. 4. Each piston 20 is formed with four main piston ports A, B, C and D, which are equally spaced about the periphery of the piston and which extend longitudinally thereof. The piston 20 comprises a cylindrical wall 21 interiorly and transversely divided by a partition 22. Two of the ports, or those indicated by the letters A and B, are formed through the cylindrical wall 21 and communicating with one end of the piston, while the piston ports C and D are formed through the piston wall 21 and communicating with the opposite end of the piston. In order that the ports may extend longitudinally for a distance greater than one-half the length of the piston, those portions of the ports extending beyond the partition are enclosed by side and bottom walls, as illustrated. Throughout the entire length of the ports A and B they communicate solely with one end of the piston, while throughout their entire length the ports C and D communicate solely with the interior of the opposite end of the piston.

Each piston is likewise formed with a shallow auxiliary passageway K along its bottom surface extending short of the ends of the piston, as illustrated.

As before stated, the pistons 20 are mounted for reciprocating and oscillatory movement in the cylinders 19 and it is intended that they revolve about their axes during their endwise movement in order that the registration of the ports A, B, C and D and the auxiliary passageway K with the main cylinder ports E, F, G and H and auxiliary cylinder ports J may be effected at properly timed intervals to effect the operation of the meter, as will be described.

In general, assuming that the piston is centrally located in the cylinder, two of the piston ports A and B will be in register with the inlet ports E and F of the cylinder 19 so that fluid from the inlet chamber 15 of the meter casing

will enter into the end X of the cylinder communicating with the inlet ports through the piston ports A and B and by its pressure move the piston toward the opposite end XX of the cylinder. At the same time the other two piston ports C and D will be in register with the outlet ports G and H of the cylinder so that as the liquid is displaced in the end of the cylinder XX communicating with the outlet ports G and H through the piston ports C and D, it will pass through the piston ports C and D and the outlet ports G and H into the outlet chamber 17 of the meter casing and discharge through the outlet connection. However, as the piston moves endwise, it likewise revolves in order that at the end of its displacement stroke, it can reverse the registration of the ports so that the piston will be driven in the opposite direction by the pressure of the inlet fluid.

To revolve the pistons and also to operate the same in synchronism, they are each connected by centrally located radially projecting crank arms 24 and gears to a common crank member 25 at ninety degrees apart. This crank member operates in a plane parallel to the axis of reciprocation of the pistons so that as the latter move endwise, the crank is revolved and by so doing turns the pistons on their axes first in one direction and then the other during each complete cycle of the crank.

As the piston cranks are ninety degrees apart, one will be on dead center while the other will be half-way through a displacement stroke and will constitute the medium for moving the piston on dead center past dead center so that it may commence its displacement stroke, all as taught by the aforesaid patent. However, if the cylinder ports are closed prior to dead center and not opened again until after dead center is past, compression at one end of the cylinder and a tendency to create a vacuum occurs between closing of the ports and dead center and again, but in reverse order, between dead center and opening of the ports. This cannot be avoided because it is practically impossible mechanically to effect a seal by the piston between the ports at only precisely dead center because an appreciable overlap of piston surface and cylinder port edge is necessary to effect such a seal.

The effect of such compression and tendency to create a vacuum is to increase the energy consumed in operating the meter which results in pressure drop across the meter and detracts from the efficiency of the meter.

I eliminate such compression and tendency to create a vacuum in the present meter by its improved construction and port arrangement. To illustrate this I shall describe one cycle of operation of one piston of the meter.

Assuming that the piston 20 is at the center of its stroke, as illustrated in Figs. 5 and 6, and it is moving in a direction toward the end XX of the cylinder, the piston ports A and B in the end of the piston 20 communicating with the end X of the cylinder 19 will be in communication with the two inlet ports E and F, as shown, so that the liquid from the inlet chamber 15 will enter into the end of the cylinder X, moving the piston in the direction toward the cylinder end XX. At the same time the piston 20 will be revolving slowly in the direction of the arrow a, moving the piston ports A and B toward closed position. At the same time the revolution of the piston will be moving the piston ports C and D, which are then acting as outlet ports in the end of the cylinder XX toward closed position,

At this time, of course, the fluid in the end of the cylinder **XX** is being displaced by the piston and is discharging through the piston ports **C** and **D** and the outlet ports **G** and **H** in the cylinder to the outlet chamber **17**.

As the piston **20** continues to revolve, it will assume the position shown in Figs. 7 and 8 with the closing edge of the piston ports **A** and **B** in exact register with the edge of the inlet ports **E** and **F**, as shown. At this time the opening edge of the auxiliary passage **K** in the piston **20** is in exact register with the edge of the auxiliary port **J** in the end **XX** of the cylinder. However, at this time the relationship between the piston ports **A**, **B**, **C** and **D** and the cylinder ports **E**, **F**, **G** and **H** is such that the ports **C** and **D** are not as yet closed. At this time the position of the piston crank is such that the crank will be approximately five degrees ahead of dead center so that a slight additional amount of endwise travel of the piston **20** is necessary before dead center is reached, so that at dead center the closing edges of the piston ports **A** and **B** will overlap five degrees the adjacent edges of the inlet ports **E** and **F** in the cylinder **19**, and the auxiliary port **J** in the end **X** of the cylinder will be in full register with the auxiliary piston passage **K**, as shown in Fig. 8, so as to admit fluid through the auxiliary port **J** into the end **X** of the cylinder to prevent a tendency to create a vacuum. The passageway **K** will, of course, as shown, establish communication between the end of the cylinder **X** and the auxiliary passageway **J** and the outlet chamber **17** through the outlet port **H**.

At the same time in the end **XX** of the cylinder the ports **C** and **D** have not as yet ceased to register with the ports **G** and **H** so that between the closing of the inlet ports **E** and **F** and the five degrees of additional travel to dead center no compression will be created due to the fact that the fluid may still discharge through the piston ports **C** and **D** and out through the outlet ports **G** and **H** in the cylinder. That is to say, that when the piston passes dead center and commences to move toward the end **X** of the cylinder, there is still communication between the end **XX** of the cylinder and the outlet chamber.

It is desired to point out that as the piston continues to revolve in the same direction, the ports **A** and **B** of the piston become the discharge or outlet ports for the end **X** of the cylinder, while the piston ports **C** and **D** become the inlet ports for the end **XX** of the cylinder.

Assuming now that dead center is precisely reached, as the piston continues to travel in the direction of the arrow *a*, the closing edge of the piston ports **C** and **D** will register with the edge of the outlet ports **G** and **H** in the cylinder **19** sometime between dead center and five degrees beyond dead center, or until the parts reach the position shown in Figs. 11 and 12. At this point the ports **A** and **B** have registered with the outlet ports **G** and **H** to form a communication between the end **X** of the cylinder and the outlet chamber **17**. The commencement of registration of the ports **A** and **B** with the outlet ports **G** and **H** of the cylinder occurs sometime within five degrees of dead center, or after their closing edges have passed the edges of the inlet ports. From this point on, the cycle of operation in the end **XX** of the cylinder and the cooperation between the piston ports and auxiliary passageway **K** and the inlet, outlet and auxiliary ports of the cylinder is the same in end **XX** of

the cylinder **19** just as described in connection with end **X** of the cylinder.

I desire to point out, however, that as the piston moved toward the end **XX** and the closing edge of the piston ports **A** and **B** registered with the edge of the inlet cylinder ports **E** and **F** to close the same, the auxiliary passage **K** of the piston registered with the edge of the auxiliary port in the cylinder so as to open this port into communication with the end **X** of the cylinder **19** just as the inlet cylinder ports **E** and **F** are closed. This is so that fluid may enter the end **X** of the cylinder **19** during the time that the inlet ports **E** and **F** of the cylinder **19** are closed to the end **X** of the cylinder **19**, and registration of the auxiliary passageway **K** in the piston **20** with the auxiliary port **J** in the cylinder continues throughout the time that the inlet ports **E** and **F** in the cylinder are closed to the end **X** of the cylinder. Consequently, the auxiliary passage **K** in the piston does not go out of register with the auxiliary port **J** in the cylinder **19** at the end **X** of the cylinder until the ports **A** and **B** come into register with the outlet ports **G** and **H** of the cylinder, at which time, of course, the auxiliary passage **K** goes out of register with the auxiliary port **J** in the end **X** of the cylinder. The auxiliary passage **K** at the opposite end of the piston cooperates with the auxiliary port **J** in the end **XX** of the cylinder in exactly the same fashion.

Therefore, it is seen that as the piston **20** advances on a displacement stroke, no compression can possibly occur just prior to dead center due to the fact that there is a constant communication between the end of the cylinder in which the liquid is being displaced and the outlet chamber **17** at all times during the displacement stroke of the piston **20**. Likewise, the end of the cylinder in which fluid is to be displaced on the succeeding piston stroke is in communication with the outlet ports **G** and **H** through the auxiliary port **J** and passage **K** during the time that it is out of communication with the inlet chamber, so that there can be no tendency to create a vacuum therein.

Also, it is seen that when the piston ends its advance on a displacement stroke and commences the opposite displacement stroke, no vacuum can occur at the filled end of the cylinder due to the fact that the auxiliary passageway **K** will be in communication with the auxiliary port **J**, and no compression can be had at the opposite end of the cylinder due to the fact that it will be in communication with the outlet port. Therefore, it is seen that by my invention I have eliminated in meters of the character referred to any possibility of compression and a tendency to effect a vacuum at the ends of the piston strokes, and thus I have minimized the amount of energy necessary to operate the piston and have reduced the pressure drop across the meter to a minimum. Obviously when the pistons reciprocate, they will drive the crank mechanism, and this crank mechanism in addition to synchronizing the operation of the pistons is connected with the counter mechanism of the meter to count or register the piston strokes and interpret the same into gallons or other units of liquid measure.

While I have shown the preferred form of my invention, it is to be understood that various changes may be made in its construction by those skilled in the art without departing from the spirit of the invention as defined in the appended claims.

Having thus described my invention, what I

claim and desire to secure by Letters Patent is:

1. A fluid meter comprising a meter casing having a pair of cylinders formed therein, each cylinder being formed with a pair of inlet ports and a pair of outlet ports alternately arranged with relation to the inlet ports, a piston in each cylinder, a central transverse partition in each piston, two pairs of ports in the periphery of each piston, each pair of ports being in communication with opposite ends of the piston, means to cause the pistons to oscillate in synchronism upon reciprocable movement thereof, said ports being so disposed that one pair in each piston registers with the inlet ports and the other pair with the outlet ports and being so spaced as to alternately register with the inlet and outlet ports in the cylinders upon oscillation of the piston, and complementary auxiliary port and passageway means at opposite ends of each cylinder and piston for alternately establishing communication between the cylinder ends and the outlet ports during the time commencing when said ends are out of communication with the inlet ports and enduring to the time said ends are placed in communication with the outlet ports by the piston ports.

2. A fluid meter comprising a meter casing having a pair of cylinders formed therein, each cylinder being formed with a pair of inlet ports and a pair of outlet ports alternately arranged with relation to the inlet ports, a piston in each cylinder, a central transverse partition in each piston, two pairs of ports in the periphery of each piston, each pair of ports being in communication with opposite ends of the piston, means to cause the pistons to oscillate in synchronism upon reciprocable movement thereof, said ports being so relatively disposed and the oscillatory stroke of each piston being such that the pairs of piston ports alternately register with the inlet and outlet ports with one pair of piston ports in each piston becoming out of register with the inlet ports and subsequently in register with the outlet ports prior to the other pair of piston ports becoming out of register with the outlet ports and subsequently coming into register with the inlet ports, and complementary auxiliary port and passageway means at opposite ends of each cylinder and piston for alternately establishing communication between the cylinder ends and the outlet ports during the time commencing when said cylinder ends are out of communication with said inlet ports and enduring until the time said ends are placed in communication with the outlet ports by the piston ports.

3. A fluid meter comprising a meter casing having a pair of cylinders formed therein, each cylinder being formed with a pair of inlet ports and a pair of outlet ports alternately arranged with relation to the inlet ports, a piston in each cylinder,

der, a central transverse partition in each piston, two pairs of ports in the periphery of each piston, each pair of ports being in communication with opposite ends of the piston, means to cause the pistons to oscillate in synchronism upon reciprocable movement thereof, said ports being so disposed that one pair in each piston registers with the inlet ports and the other pair with the outlet ports and being so spaced as to alternately register with the inlet and outlet ports in the cylinders upon oscillation of the piston, each of said cylinders being formed with auxiliary ports, each of said pistons being formed with auxiliary passageways in its peripheral surface to cooperate with said auxiliary ports, said auxiliary ports and passageways being so relatively disposed and so relatively positioned with respect to the other ports as to alternately establish communication between the cylinder ends and the outlet ports during the time commencing when said ends are out of communication with the inlet ports and enduring until the time said ends are placed in communication with the outlet ports by the piston ports.

4. A fluid meter comprising a meter casing having a pair of cylinders formed therein, each cylinder being formed with a pair of inlet ports and a pair of outlet ports alternately arranged with relation to the inlet ports, a piston in each cylinder, a central transverse partition in each piston, two pairs of ports in the periphery of each piston, each pair of ports being in communication with opposite ends of the piston, means to cause the pistons to oscillate in synchronism upon reciprocable movement thereof, said ports being so relatively disposed and the oscillatory stroke of each piston being such that the pairs of piston ports alternately register with the inlet and outlet ports with one pair of piston ports in each piston becoming out of register with the inlet ports and subsequently in register with the outlet ports prior to the other pair of piston ports becoming out of register with the outlet ports and subsequently coming into register with the inlet ports, each of said cylinders being formed with auxiliary ports, each of said pistons being formed with auxiliary passageways in its peripheral surface to cooperate with said auxiliary ports, said auxiliary ports and passageways being so relatively disposed and so relatively positioned with respect to the other ports as to alternately establish communication between the cylinder ends and the outlet ports during the time commencing when said ends are out of communication with the inlet ports and enduring until the time said ends are placed in communication with the outlet ports by the piston ports.

WILLIAM F. BERCK.
